UNITED STATES PATENT OFFICE.

HOWARD DE WOLFE SAWYER, OF REVERE, MASSACHUSETTS, ASSIGNOR
TO DANIEL W. WORMWOOD, OF CHELSEA, MASSACHUSETTS.

COOKING AND HEATING STOVE.

SPECIFICATION forming part of Letters Patent No. 588,884, dated August 24, 1897.

Application filed July 12, 1895. Serial No. 555,760. (No model.)

To all whom it may concern:

Be it known that I, HOWARD DE WOLFE SAWYER, of Revere, in the county of Suffolk and State of Massachusetts, have invented certain new and useful Improvements in Down-draft Cooking and Heating Stoves, of which the following, taken in connection with the accompanying drawings, is a specification.

The object of my invention is to provide a cooking and heating stove or range in which the draft is downward through the fire and through its supporting-grate, formed of water-containing tubes supplied from below with water which rises from the grate between the fire-pot and oven and by its circulation serves to heat adjacent rooms. The caloric-current after thus descending passes under, upwardly, beyond, and over the oven, thus entirely encircling it and heating, last of all, the top, through which griddle-holes are formed. Water-walls and bottom are provided for the fire-pot and combustion-chamber and flow and return pipes afford constant circulation for the water. Supply-pipes lead obliquely upward beneath the oven and connect the extreme inner end of the water-bottom with the bottom portion of the water-back, which stands vertically between the fire-pot and oven. Fuel is supplied through griddle-holes over the water-grate. An open air-space may be interposed between the oven and the combustion-chamber or other part of the caloric-passage to temper the heat, if required. A broiler-opening through the front wall is provided at the line of the top of the fire. The fumes of cooking are drawn downwardly into the fire. An ash-door near the bottom permits necessary cleaning out. A horizontal recess in the front wall of the fire-pot and furnished with a door permits ready insertion of the grate-tubes and their supply-pipes and affords space for movement of the water-box due to expansion or contraction of the parts. The grate may, however, be arranged otherwise than as herein illustrated, the downward draft being assured. The walls, the bottom, and the grate and supply-pipes being all filled with water and exposed to the heat simultaneously, expansion will be practically uniform, and the tubes may run from wall to wall obliquely to promote active circulation.

The fire-box with its back and walls and the water-bottom with tubular water-passages from its tip to the lower part of the water-back may be cast in one and used integral in 55 heaters of proper size.

In the drawings, Figure 1 is a vertical longitudinal section through one of my improved stoves. Fig. 2 is a perspective detail, in section, of the fire-box and water-bottom detached and somewhat modified in form.

The central feature of my stove or range is the oven A, surrounded by the fire-pot B and the continuous passage C C for the caloric-current. (Shown in Fig. 1 and denoted by the 65 darts.) The hollow bottom D and vertical walls E are filled with water, as is the water-back F, interposed between the fire-pot and the oven, the entire water-space being connected for free circulation. The grate G and its supply-pipes H enter the water-back F, and converging, as shown, both enter the water-box J, which extends horizontally across the front of the stove, but is free from contact with its walls, thus giving freedom of expansion and 70 contraction and providing for active circulation of the water therein.

The water-box J occupies a recess in the front wall of the stove, in which it may move slightly and through which the grate-tubes 80 G and supply-pipes H may be first introduced in setting up the stove. A door j may close this recess tightly in the front to prevent entrance of air or escape of gases.

Beneath the oven pipes K run obliquely 85 from the lower end of the water-back F to the inner end of the hollow bottom D, where they enter a turned-up foot or boss d, into which their ends are screwed, so that the water may rise therein and circulate freely as it becomes 90 heated by the high temperature of the burning gases. The connection of the parts shown gives free expansion and contraction to said bottom and pipes K, since they are not connected laterally with the shell of the stove, 95 and can yield lengthwise as can the grate G, pipes H, and box J. The current is downward through the grate and fire thereon, and it impinges with great heating effect upon this yielding bottom and the pipes K, which 100 cross its path. The current is deflected upwardly by the foot d and continues back of

and over the oven to the funnel L. The foot d is preferably a transverse shell covering an opening at the tip of the water-bottom D and bolted in place.

- 5 In view of the great heat produced by the downward draft under the arrangement shown I provide between the oven and the passage C C an air-space M, into which more or less of external air may be admitted through 10 openings O, controlled by suitable slides. A hot closet P, adjoining the upright passage C, is abundantly heated by the current impinging on the end wall and rising in said passage.
- 15 Griddle-holes with suitable covers Q are formed over the fire-pot B and oven A, the first of these constituting the draft-opening above the fire. A broiler-opening R may also be formed just above the fire-level in the 20 front wall. This may serve to admit the draft when the griddle-holes are occupied by kettles or otherwise. The ash-door U opens through the front wall into the combustion-chamber beneath the grate for removal of 25 ashes.

My stove or range is of great utility for heating adjacent rooms by hot-water circulation. To promote this, I extend flow-pipes S upwardly from the top of the water-back F 30 within or near to the funnel L, so as to utilize the heat remaining in the caloric current. Such pipes S run to radiators in the various rooms to be heated and return thence to the lower part or hollow bottom D through return-pipes T.

I am aware that in the patents to Easterly, dated February 13, 1855, reissue No. 3,010, June 30, 1868, and to Field, dated July 19, 1859, No. 24,800, magazine cooking-stoves are 35 shown having a fuel-chamber external to the shell or body of the stove, with draft-inlets through such external chamber and tubular grates at the base thereof level with the stove-top and not connected with any water-walls in the fire-box or stove-body; and also that 40 in the Backus patent, No. 132,129, dated October 15, 1872, water-walls are shown without water-grate or downward draft, and in the Dewey patent, No. 70,077, dated October 22, 45 1867, water-walls without downward draft and a water-grate without circulation through it are shown. In the Backus and the Dewey patents the oven is outside of the stove-body proper. I therefore disclaim all these prior 50 constructions, each one failing to embody the combination and arrangement of parts which renders my stove so effective.

I claim as my invention—

1. In a downdraft cook stove or range, the fire-pot and the oven, both within the shell 60 or body of the stove proper, and the water-back F immediately between them, in combination with the tubular grate G through which water circulates freely, and a draft-inlet through the stove-body above the grate, 65 admitting air downwardly between the grate-bars, and with the caloric-passage C C C surrounding the oven, substantially as set forth.

2. In a downdraft cook stove or range, the interior oven, in combination with the fire-pot within the stove-body and having water-walls, a tubular water-grate therein and a draft-inlet above said grate, and with a caloric-passage from such fire-pot extending beneath, beyond and over the oven, substantially as set forth. 75

3. In a downdraft cooking and heating stove, the interior oven and the caloric-passage surrounding said oven, in combination with the fire-pot having a water-back with 80 water-grate connected thereto and a water-bottom extending beneath the oven, and with inclined water-pipes beneath the oven within the caloric passage and connecting the extension of said bottom with the water-back, 85 substantially as set forth.

4. In a downdraft cooking and heating stove, the oven A, inclosed within the shell or body of the stove proper, and the heat-passage C C C encircling the oven, in combination with the fire-pot having a water-bottom and water-back, an inclosed water-grate 90 communicating with said water-back, a draft-inlet above said grate whereby a downward draft is assured, and flow and return pipes for 95 hot-water circulation to adjacent rooms, substantially as set forth.

5. In a downdraft heating apparatus, the fire-pot having a water-back and a tubular water-grate communicating therewith and 100 extending forward therefrom, in combination with a draft-inlet above the grate, a water-bottom beneath the grate and fire-pot and running rearwardly beyond said water-back, and a tubular connection between the tip of 105 said water-bottom and the lower part of the water-back, substantially as set forth.

In testimony whereof I have signed my name to this specification, in the presence of two subscribing witnesses, on this 25th day 110 of June, A. D. 1895.

HOWARD DE WOLFE SAWYER.
